UNITED STATES PATENT OFFICE.

JOSEF HENRIK HALLBERG, OF NEW YORK, N. Y., ASSIGNOR TO GENERAL INCANDESCENT ARC LIGHT COMPANY, OF NEW YORK, A CORPORATION.

REGULATOR FOR ALTERNATING SERIES ARC-LIGHT SYSTEMS.

SPECIFICATION forming part of Letters Patent No. 766,824, dated August 9, 1904.

Application filed January 29, 1902. Serial No. 91,733. (No model.)

To all whom it may concern:

Be it known that I, JOSEF HENRIK HALLBERG, a citizen of the United States, residing at New York city, county and State of New York, 5 have invented certain new and useful Improvements in Regulators for Alternating Series Arc-Light Systems, of which the following is a specification.

My invention relates to a device adapted to 10 be connected in series with the generator and arc-lamps of an alternating series arc-light system, and which has for its purpose to maintain the current on the line constant irrespective of the number of lamps in operation.

15 A further object of my invention is to simplify the construction and decrease the cost of such transformer.

The accompanying diagrammatic drawings 20 will serve to illustrate my invention.

Figure 1 is a vertical section through the inclosing case of a regulator, showing the movable core of the device supported upon a buoyant device which is immersed in a body of oil. Fig. 2 is a similar view showing the core 25 suspended from a buoyant device.

In the drawings, 5 represents a suitable inclosing case with a removable cover 6. The interior of the case is adapted to be partially filled with a body of oil 7 or other insulating 30 fluid. In the construction shown in Fig. 1 a smaller body of oil is required than that shown in Fig. 2. Located within the case and suitably supported therein in any convenient manner are a pair of solenoidal magnets 8. Arranged to have a vertical motion in such magnets is a core 9.

10 represents a float connected to the core 9 through the rod 11. In Fig. 1 the float is shown as attached to the bottom of the rod 40 and in Fig. 2 near to the top of the rod. Secured to the top of the rod are the removable weights 12.

13 represents a disk of wood or other material, connected in Fig. 1 to the bottom of the 45 float 10 and in Fig. 2 to the bottom of the core 9. The disk in Fig. 2 is provided with relief-valves 14 15. Located under the disk 13, Fig.

2, is a spring 16, which has for its purpose to cushion the downward movement of the core 9.

17 represents weights which may be attached to the floats 10 for the purpose of decreasing the buoyancy of the floats; 18, lamps in the lamp-circuit.

The operation of the device is as follows: When the resistance of the lamp-circuit is 55 altered by cutting a lamp or lamps into or out of circuit, as the case may be, the attractive power of the solenoids 8 is altered. In the first instance when a lamp (or lamps) is cut in the power of the solenoids is decreased. In 60 the second instance when a lamp (or lamps) is cut out the power of the solenoids is increased, with the effect of removing from or introducing into the lamp-circuit an impedance corresponding to the resistance of the lamps 65 cut in or out. The position of the core 9 relative to the solenoids 8 may be regulated by adjusting the weights 12 and 17 to compensate for any variation in current strength in the lamp-circuit.

I do not limit myself to any special form of solenoid, core, or buoyant device for carrying and balancing the weight of the core, as many changes may be made in such parts without affecting the intent of my invention. 75

Having thus described my invention, I claim—

1. In a regulator for alternating series arc-light systems, the combination of an inclosing case, a body of oil, a solenoidal magnet, located within the case, a movable core for said magnet, and a buoyant device floating in said body of oil and adapted to support and overcome the normal weight of said core.

2. In a regulator for alternating series arc-light systems, the combination of an inclosing case, a body of oil, a solenoidal magnet located within the case, a movable core for said magnet, a buoyant device floating in said body of oil, and adapted to support and overcome the normal weight of the core, and means for adjusting the displacement of the float.

3. In a system of electrical distribution, a regulating reactance-coil having a moving

part adapted to increase the choking effect in said coil, a float connected to said moving part and adapted to move out of a liquid as the magnetic pull of the reactance-coil is increased.

4. In an electric-lighting system, a regulating reactance-coil having a moving part adapted to increase the choking effect in the said coil, a number of arc-lamps in series with the said coil, and a float partially immersed in a liquid and attached to the said moving part,

the said float being so shaped as to displace increasing amounts of liquid per unit of immersion in the same proportion as the magnetic pull of the reactance-coil decreases.

In testimony whereof I affix my signature in the presence of two witnesses.

JOSEF HENRIK HALLBERG.
